UNITED STATES PATENT OFFICE.

GAIUS CLEVELAND HUNTER, OF BUFFALO, NEW YORK.

FIGURE WHEELED TOY.

Application filed March 23, 1927. Serial No. 177,757.

My invention relates to improvements in children's play toys and the object of the invention is to construct a vehicular toy of captivating appearance and constituting a model of an automobile body provided with a propeller, wings, tail, and running wheels, a further object of the invention is to swingably mount the wings upon the body and to provide means extending between a live axle and the wings so that they flap when the toy is propelled along a surface.

Another object of the invention is to provide a pilot or driver within the body of the toy which shall bob up and down as the wings flap, and another object of the invention is to construct the body portion of the toy of a single sheet of material which is suitably formed so that the cost is reduced to a minimum and well within reach of the average child's purse.

My invention consists of a toy constructed and arranged all as hereinafter more particularly described and illustrated in the accompanying drawings in which:

Figure 1 is a plan view of the toy.

Figure 2 is a side elevational view thereof.

Figure 3 is a longitudinal sectional view taken through the line 3—3 figure 1.

Figure 4 is a plan view of the unitary blank from which the body of the toy is formed.

Figure 5 is a perspective view of one of the wings showing the lugs formed thereon, and by means of which the wings are swingably mounted upon the body of the toy.

Figure 6 is a fragmentary view of the upper portion of the body and upon which the wings are swingably mounted, and,

Figure 7 is a side elevational view of one of a pair of U-shaped wire members which are used as a connecting means between the body and the wings.

Like characters of reference indicate corresponding parts in the different views.

The body of the toy is formed from a unitary sheet of material as illustrated in Figure 4 and consists of two side members of the body 1 and 2 connected by a member 3 which constitutes the top of the body when the blank is formed. Intermediately of their length the members 1 and 2 are shaped to form the sides of what I will call the passenger compartment and also the hood and fuselage portion of the toy, the forward portions 4 and 5 of the members 1 and 2 form the complete hood, being each fur-

nished with folding lines 6 and slits 7 so that when the members 1 and 2 are pressed downwardly about the member 3 the inner parts 8 and 9 of the portions 4 and 5 may be bent downwardly to the extent of the slits 7 to form the top of the hood, the free edges 10 thereof of course being suitably folded together. The radiator portion of the hood is formed by the parts 11 and 12 of the portions which are bent along the folding lines 6 so that they overlap each other, the lugs 13 which are formed thereon overlapping and constituting a forward support for the propeller rod which shall be hereinafter described.

In the vicinity of the forward and rear transverse edges of the member 3 I form folding lines 14 and 15 to permit the portions 16 and 17 between such folding lines and the adjacent edges to be folded downwardly to form the wing supporting means which shall also be hereinafter described. The fuselage portions 18 and 19 are brought together in substantially V shaped form as shown in Figure 1 and clipped together in the usual manner by means of lugs 20 formed on the portion 19, the rear parts 21 and 22 of such portions being bent to form a U shaped member 23 which constitutes a limiting means for the swinging movement of the tail.

Interiorly of the body portion I furnish a swingable rocker arm member 24 which is of the same general form as illustrated in Figure 3, its upper portion being shaped to constitute the head and shoulders of the pilot 25, this member 24 necessarily consists of two similar portions held together by clips 26 as the propeller rod 27 which extends through the lugs 13 on the hood and through an orifice 28 in the turned down portion 17 lies directly above the rocker arm member and as it is necessary to give the toy a realistic appearance the pilot's side face should be seen upon each side of the propeller rod. The rear end of the rocker arm is pivotally mounted upon a pin 128 which extends through the side portions 18 and 19 of the fuselage and held in position by lugs 29 which are turned over its ends.

The tail member is blanked from a unitary sheet of material and consists of a pair of vertically disposed members 30 of U shaped form and between which the rear running wheel 31 is freely mounted, the forward portion of such members being

formed to provide upper and lower loops 32 into which a pin 33 is freely inserted, such pin being held about its center by a V shaped member 34 which passes upon each side of 5 the rear portion of the rocker arm 24, and through which the pin 28 also extends, the upper corners of the V shaped member 34 being furnished with lugs 35 which are bent over the upper edges of the fuselage in order 10 to prevent the member from swinging about the pin 28. The tail members 30 are of course bent along their lower edges to form the horizontal tail planes 36.

The toy is supported upon a pair of front 15 running wheels 37 which are secured upon a live axle 38 having a crank 39 formed centrally thereof and of course positioned interiorly of the body, and 40 is a slot pressed from the rocker arm 24 and through 20 which the crank extends so that the arm rocks under the influence of the rotative movement of the crank.

41 and 42 are the two forward planes or wings each being furnished upon their 25 inner corners with lugs 43 and 44 which extend over the outer side faces of the turned down portions 16 and 17, aligned orifices 45 and 46 being furnished in the lugs and turned down members so that the wings 30 may be pivotally mounted upon the toy by a pair of rods which each extend through such aligned pairs of orifices. In order to 35 simplify the construction of my toy I have made each of these rod members 47 of U shaped form, their free ends 48 being bent at right angles to the main portion and when the toy is being assembled it is only necessary to hold a wing so that the orifices in its lugs coincide with the orifices in the 40 body and compress the free ends of one of the U shaped members 47 together so that it can be inserted up into the body and when it is in position may spring outwardly so that the bent ends 48 pass through the 45 orifices 45 and 46 and so swingably secure the wing upon the body, and the other wing is of course secured in place in a similar manner. In order that the wings may have a flapping movement when the toy is propelled along a surface I connect them to the 50 rocker arm 24 in the following manner.

Upon each of the pair of members which constitutes the rocker arm 24 I form a transverse lug 49 in the vicinity of the rear

edges of the wings and I also form the lugs 55 44 upon the wings of extended form and bent upwardly to a slight degree to constitute arms, and 50 and 51 are links connecting the lugs 49 to the respective arms upon the wings. It will be readily seen as the 60 rocker arm 24 oscillates under the influence of the crank 39 that the links 50 and 51 will move upwardly and downwardly and flap the wings. As the head and shoulders of the pilot are formed to bob into and out of 65 the body an orifice 52 is furnished in the member 3 and the mechanism is so constructed that the pilot's head projects above the body when the wings are down and bobs into the body when the wings are up. To 70 give the device a more realistic appearance I furnish a freely mounted propeller 53 upon the outer end of the propeller rod 27, the propeller being constructed of very light material such as celluloid so that it will 75 freely rotate of its own accord as the toy is propelled forwardly.

From the foregoing description it will be seen that I have constructed a toy combining the principal features of an automobile 80 and a flying machine and in which the wings will flap and the pilot move as the toy is propelled forwardly, and furthermore I have devised a toy of extremely simple construction and of a form which can be manufactured and sold at a low cost.

What I claim as my invention is:

A toy of the character described comprising a body member simulating a combination of an enclosed automobile and flying 90 machine, said body member which comprises a hood, passenger compartment and fuselage being formed of a unitary piece of material, running wheels upon which the body is mounted, a tail member mounted 95 upon a running wheel and pivotally secured to the rear end of the fuselage, wings simulating flying machine wings swingably mounted upon the body, a rocker arm positioned within the body and connected to the running wheels so that it oscillates as the toy is propelled, a figure formed in the rocker arm to simulate the driver of the toy, and means connecting the rocker arm to the wings so that the wings flap as the 100 rocker arm oscillates when the toy is propelled.

GAIUS CLEVELAND HUNTER.
